(57) **CLAIM**

The ornamental design for a display panel or screen with a graphical user interface, as shown and described.

DESCRIPTION

FIG. 1 is a front elevational view of a first image of a display panel or screen with a graphical user interface showing our new design;

FIG. 2 is a front elevational view of a second image thereof; FIG. 3 is a front elevational view of a third image thereof; FIG. 4 is a front elevational view of a fourth image thereof; FIG. 5 is a front elevational view of a fifth image thereof; FIG. 6 is a front elevational view of a sixth image thereof; and FIG. 7 is a front elevational view of a seventh image thereof. FIG. 8 is a front elevational view of an eighth image thereof; FIG. 9 is a front elevational view of a ninth image thereof; and,

FIG. 10 is a front elevational view of a tenth image thereof. The appearance of the transitional image transitions sequentially between the images shown in FIGS. 1-10. The process or period in which an image transitions to another forms no part of the claimed design.

The broken line showing of a display panel or screen, and graphical user interface elements forms no part of the claimed design.
